UNITED STATES PATENT OFFICE

163,377

AQUARIUM UNIT

Louis Feldman, New York, N. Y.

Application May 23, 1949, Serial No. 2,828

Term of patent 7 years

(Cl. D91—2)

To all whom it may concern:

Be it known that I, Louis Feldman, a citizen of the United States, residing at 644 Water Street, New York city, county and State of New York, have invented a new, original, and ornamental Design for an Aquarium Unit, of which the following is a specification, reference being had to the accompanying drawing, forming part thereof, and in which:

Figure 1 is a perspective view of an aquarium unit, as seen from the front, and showing my new design.

Figure 2 is a perspective view of same, as seen from the rear.

I claim:

The ornamental design for an aquarium unit, as shown.

LOUIS FELDMAN.
